Filed Mar. 13, 1968, Ser. No. 10,954

Term of patent 14 years

Int. Cl. D6—01

U.S. Cl. D15—11

FIGURE 1 is a front perspective view of a bench showing our design;

FIGURE 2 is a fragmentary plan view showing the right end portion of the bench of FIGURE 1 on an enlarged scale; and

FIGURE 3 is a fragmentary end elevational view thereof.

The legs of the bench are shown broken away at the ends thereof to indicate indeterminate length.

The end of the bench not shown is a mirror image of the end shown while the back is plain and unornamented.

We claim:

The ornamental design for a stadium bench, as shown and described.
